GOLF CLUB HEAD COVER

James E. Noonan, Peoria, Ill.

Application November 28, 1956, Serial No. 43,969

Term of patent 14 years

(Cl. D34—5)

FIG. 1.

FIG. 2.

FIG. 3.

FIG. 4.

Fig. 1 is a front elevational view of the golf club head cover comprising my design.

Fig. 2 is a side elevational view of the cover shown in Fig. 1.

Fig. 3 is a rear face view of the cover.

Fig. 4 is a top plan view of the cover. The stippling is intended to indicate a color contrasting with the un-stippled portion of the cover.

I claim:

The ornamental design for a golf club head cover, substantially as shown.
